CHARLES F. LEEFEVER, OF PLYMOUTH, MICHIGAN, ASSIGNOR TO DAISY MANUFACTURING COMPANY, OF PLYMOUTH, MICHIGAN, A CORPORATION OF MICHIGAN

MAGAZINE BARREL FOR GUNS

Application filed February 18, 1929. Serial No. 340,978.

The invention relates to guns and more particularly to air guns which are provided with an outer or false barrel within which is arranged the shooting barrel and an adjacent magazine barrel. It is the object of the present invention to obtain a construction of combined shooting and magazine barrel insertable in the false barrel and which has various advantages such as simplicity in construction, greater strength and rigidity. To this end the invention consists in the construction as hereinafter set forth.

In the drawing:

Figure 1 is a longitudinal section through the false barrel of a gun showing my improved magazine and shooting barrel construction engaged therewith;

Figure 2 is an enlarged cross section of Figure 1;

Figure 3 is a similar view of a modified construction.

Figure 4 is a perspective view of the magazine and shooting barrel detached.

In the present state of the art, it is usual to form the shooting barrel and the magazine barrel of two separate members which are attached to each other with provision for discharging the shot from the magazine through an aperture into the shooting barrel. It is one of the features of my improvement that the magazine and shooting barrels are formed from a single blank and are therefore integral with each other. This imparts greater strength and rigidity, as each of the barrels forms a truss or reinforcement for the other. It is, however, necessary to avoid any crevice in the shooting barrel which would permit the escape of air and I have therefore provided a seamless tube which forms a liner for said barrel and effectively seals the same.

As shown in Figures 1 and 2, a sheet metal blank is bent into a substantially S-shaped cross section A and having the lower shooting barrel cylinder portion A', the upper magazine barrel cylinder portion A² with the connection portion A³ in common to the two barrels. The opposite ends of the member A are fashioned for engagement respectively with the screw threaded plug or bushing B

which detachably engages the piston abutment B' in the false barrel and the cap member C for closing the muzzle end of the false barrel. As shown, the attachments are formed by extensions A⁴ A⁵ of the portion A' 55 which are inserted respectively in the plug B and cap C and are brazed or otherwise rigidly secured thereto. Adjacent to the plug B the true barrel A' is cut away at D to receive the shot from the magazine barrel and the end portion of said magazine barrel is rounded over as indicated at E to guide the shot through said aperture. The portion A² is not completely closed into cylindrical form but terminated so as to leave a longitudinal slot 60 F extending the entire length thereof and permitting the passage of a lug or finger piece G on the shot follower H. This follower H also engages one end of the spring I which urges it in a direction to discharge the 65 shot, the opposite end of said spring abutting against the cap member C. To permit of introducing the spring and shot follower into the magazine barrel the latter is slotted at its rear end to form a bendable tongue J and this 70 tongue is first bent outward sufficiently to permit of the introduction of the follower and spring after which it is closed to retain said parts from accidental displacement. There is also a notch K formed in the barrel 75 A² on the edge adjacent to the slot F, which notch is adapted to receive the finger piece G to lock the spring and follower in retracted position. A loading aperture L is formed 80 in the barrel A² slightly in advance of the 85 notch K and in a position to clear the follower when retracted.

The construction as thus far described is preferably formed of sheet steel which is heat treated to blue the surface thereof. After this bluing process and the straightening of the barrel to take out any warping incidental to the heat treatment, the firing barrel is completed by the insertion of a seamless tube M 95 therein. This is preferably introduced through the end engaging the plug or bushing B, said tube M being provided at its rear end with a slightly flanged or enlarged portion which limits the plug or bushing B, being provided at its rear end with a slightly 100

flanged or enlarged portion which limits the outward movement thereof. The forward end of the tube M after passing through the cap C is peened or flanged over to hold said tube permanently in position. The tube M may be made of comparatively thin metal, as the strength and rigidity of the structure is provided through the member A. Also, if so desired, the liner tube M may be made of a different metal, such for instance as brass, which has a lubricating effect on the shot when discharged from the barrel.

While the construction thus far described is as preferably formed, I may form my combined barrel as shown in Figure 3 which substitutes for the S-shaped structure a loop N. This does not, however, as completely close the shooting barrel as the construction shown in Figure 1. I therefore deem the latter construction preferable.

What I claim as my invention is:

1. In a gun, a combined shooting and magazine barrel formed of an integral sheet metal blank fashioned into cylindrical segments about two spaced parallel axes continuous throughout their length, an extension at the end of one of said segments, a head mounted on said extension to be arranged concentric to the axis thereof, and a liner tube inserted within and in direct contact with said cylindrical segment and head.

2. In an air gun, the combination with a false barrel and a piston abutment therein, of a combined shooting and magazine barrel formed from an integral sheet metal blank fashioned into cylindrical segments about two spaced parallel axes, extensions at opposite ends of one of said segments, heads mounted on said extensions to be arranged concentric to the axis thereof, one of said heads forming a bushing for engaging the piston abutment and the other a cap for the end of the false barrel, and a liner tube inserted within said heads and co-axial segment and constituting the shooting barrel, the other segment forming the magazine barrel.

3. In a gun, a combined shooting and magazine barrel formed from an integral sheet metal blank fashioned into an S-shaped cross section and a liner tube inserted within one of the segments of the S-shaped cross section.

4. In a gun, a combined shooting and magazine barrel formed of an integral sheet metal blank fashioned into an S-shaped cross section having cylindrical segments about two spaced parallel axes, one of said cylindrical segments being substantially closed and the other leaving a longitudinal slot, a liner tube inserted within the closed segment and a shot follower inserted within the other segment and having an operating finger piece projecting through said slot.

5. In a gun, the combined shooting and magazine barrel formed of an integral sheet

metal blank fashioned into an S-shaped cross section having cylindrical segments about two spaced parallel axes, one of the said segments being substantially closed and the other being slightly open to provide a longitudinally extending slot, said closed segment having extensions at opposite ends thereof, heads mounted on said extensions to be concentric with the axis thereof, a liner tube inserted within said closed segment and heads and being apertured near one end thereof to communicate with the other segment, the end of said other segment being fashioned to form a deflector for the shot into said aperture.

In testimony whereof I affix my signature.

CHARLES F. LEFEVER.
